UNITED STATES PATENT OFFICE.

CLYDE T. DEAN, OF CHICAGO, ILLINOIS.

INK-SAVING ATTACHMENT FOR EMBOSsing-PRESSES.

1,198,198.

Specification of Letters Patent. Patented Sept. 12, 1916.

Application filed August 10, 1915. Serial No. 44,716.

To all whom it may concern:

Be it known that I, CLYDE T. DEAN, citizen of the United States, residing at Chicago, in the county of Cook and State of Illinois, have invented certain new and useful Improvements in Ink-Saving Attachments for Embossing-Presses, of which the following is a specification.

The present invention relates to an ink saving attachment for embossing presses in which the surplus ink is wiped from the die or printing surface by a strip of paper preparatory to making each impression, the object of the invention being to provide novel and effective means for recovering a large portion of the ink from the wiping strip so as to prevent the waste thereof.

Further objects of the invention are to provide an ink saving attachment of this character which is comparatively simple and inexpensive in construction, which can be readily mounted upon the ordinary embossing press without necessitating any changes or alterations in the construction thereof, which will effectively soften and recover a large portion of the ink which would otherwise be wasted, and which will scrape the ink from the wiping strip without tearing or rupturing the same.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a rear elevation of the ink saving attachment, showing the same as mounted in position between the side plates of an embossing press. Fig. 2 is a transverse sectional view on the line 2—2 of Fig. 1.

Fig. 3 is an enlarged detail view of an end portion of the device, portions being broken away and shown in section to illustrate more clearly the details of construction. Fig. 4 is a detail perspective view of one end of the solvent receiving trough, showing the manner of supporting the same.

Corresponding and like parts are referred to in the following description and indicated in all the views of the drawing by the same reference characters.

For the purpose of illustration the invention is shown as mounted upon an embossing press of which fragmentary portions are shown, the numerals 1 designating the side plates of the supporting frame thereof. The 60 wiping web 2 is mounted to be moved through the embossing press in the usual manner, being unwound from a suitable feed roll and finally wound upon a suitable waste roll 3. The wiping strip is employed for removing surplus ink from the face of the die or cleaning surface, and is moved through the machine with an intermittent movement so that fresh portions of the wiping strip are brought successively into engagement with the die or printing surface. A considerable amount of ink is ordinarily removed from the die by this wiping strip, and this ink has heretofore been a total loss.

The supporting frame A of the ink saving attachment is shown as having a substantially U-shaped formation, including a horizontal cross bar 4, vertical side pieces 5, and horizontal supporting arms 6 projecting laterally in opposite directions from the upper ends of the side pieces 5 and engaging the side members 1 of the frame of the embossing press. Collars 7 are mounted upon the arms 6 so as to be susceptible of having a rotary movement thereon, although set 75 screws 8 are provided for clamping the collars in an adjusted position. Rigid with each of the collars 7 and projecting laterally therefrom is a supporting arm 9 which is provided at its free end with a notch or recess 10, said notches 10 being adapted to receive lugs 14^a upon the ends of a solvent receiving trough 14 to removably support the same. This trough 14 is provided at its ends near the top thereof with recesses 14^b 80 which open at the top of the trough, said recesses serving as bearings for the shaft 11 of a solvent distributing roller 12. With this construction the trough may be readily removed from its support and the roller 12 85 may be easily removed from the trough when desired, by merely lifting the lugs 14^a and shaft 11 from the respective recesses 10 and 14^b. This roller 12 is partially submerged in a suitable solvent 13 such as benzin which is 90 held within the trough 14. The wiping strip 2 is carried over the top of the solvent distributing roller 12 with the inky face thereof in engagement with the roller so that solvent 95 will be applied to the wiping strip in suitable 100

quantities for softening the ink thereon as the wiping strip moves rearwardly over the roller 12.

The inner faces of the side pieces 5 of the U-shaped supporting frame are provided with vertical guide-ways within which the ends of a transversely disposed knife carrying bar 15 are slidably mounted. Bearings 16 are removably fitted in suitable recesses 10 provided at the upper ends of the side bars 5, said bearings closing the upper ends of the vertical guideways 17 when in position. Journaled between the two bearings 16 is a shaft 18 upon which a backing roller 19 15 is keyed or otherwise rigidly applied. This backing roller 19 coöperates with the knife blade 20 upon the yieldably mounted bar 15 to scrape the softened ink from the wiping strip, and a suitable covering 22 of 20 felt or similar material is preferably applied to the periphery of the backing roller.

The knife blade 20 is applied to one side of the knife carrying bar 15, the opposite ends of the said bar 15 being slidably received within the guideways 17, and being engaged by springs 23 which tend to slide the bar upwardly toward the backing roller. The lower ends of the springs 23 are shown as engaged by adjusting screws 24 by means 30 of which the tension in the springs can be increased or decreased, as found most desirable.

After passing over the top of the solvent distributing roller 12 the wiping strip 2 35 is carried under the backing roller 19 and between the same and the knife blade 20, said knife blade being arranged in a plane spaced from and parallel to a plane extending through the axis of the backing roller, 40 and engaging the backing roller at the side thereof from which the wiping web 2 is drawn. From the scraping blade 20 the wiping strip 2 is drawn downwardly at a sharp angle and carried under a guide 45 roller 24, from which it passes upwardly to the waste roll 3. The guide roller 24 may be journaled within suitable ears 25 projecting rearwardly from the side pieces 5 of the supporting frame A.

50 As the wiping strip 2 moves through the machine it will be employed for removing the surplus from the die or printing surface in the usual manner and be engaged by the ink saving attachment preparatory to being wound upon the waste roll 3. The passage of the strip 2 over the solvent distributing roller 12 will rotate the latter so that solvent will be fed from the trough 14 to the inky face of the strip in sufficient quantities to 55 soften the ink thereon. The yieldably mounted scraping blade 20 will force the wiping strip into engagement with the backing roller 19 and coöperate therewith to scrape the previously softened ink from the 60 wiping strip, although the roller 19 will re-

volve as the wiping strip is advanced, thereby tending to prevent rupture or tearing of the wiping strip. The positioning of the scraping blade 20 in a plane which is spaced from and parallel to a plane passing through the axis of the backing roller 19, and on the side of the roller from which the wiping strip is drawn also tends to reduce liability of tearing or rupturing of the wiping strip. The guide roller 24 is disposed in such a 75 manner as to cause the wiping strip 2 to be drawn from the edge of the scraping blade 20 at a sharp angle, thereby causing the scraping blade to operate in the most effective manner to remove the previously softened ink from the wiping strip. The ink which is thus recovered flows or drops into an inclined chute 26 which is supported upon the lower portion of the main frame A in a position under the scraping blade. 80 From this chute 26 the recovered ink may be caused to flow into any suitable receptacle.

Having thus described the invention, what I claim as new and desire to secure by Letters Patent, is:—

1. An ink saving attachment for embossing presses and the like, including a backing roller arranged upon one side of the ink wiping strip, a yieldably mounted scraping 95 blade arranged upon the opposite side of the ink wiping strip for coöperation with the backing roller to remove the ink from the strip, means for applying a solvent to the ink wiping strip before it passes between the backing roller and the scraping blade, and means for collecting the ink recovered by the scraping blade.

2. An ink saving attachment for embossing presses and the like, including a backing roller arranged upon one side of the ink wiping strip, a scraping blade arranged upon the opposite side of the ink wiping strip and disposed in a plane parallel to and spaced from a plane passing through the 100 axis of the backing roller, said scraping blade coöperating with the backing roller to recover the ink from the ink wiping strip and being positioned on the side of the backing roller from which the ink wiping strip is 105 drawn, a guide roller around which the wiping strip passes after being drawn between the backing roller and the scraping blade, said guide roller being positioned to draw the wiping strip from the edge of the 110 scraping blade at a sharp angle to the plane of the scraping blade, and means for collecting the recovered ink.

3. An ink saving attachment for embossing presses and the like, including a 115 backing roller arranged upon one side of the ink wiping strip, a yieldably mounted scraping blade arranged upon the opposite side of the ink wiping strip and coöperating with the backing roller to remove the 120

ink therefrom, a solvent receiving trough arranged in advance of the scraping blade, distributing means for feeding solvent from the trough to the ink wiping strip, and a 5 guide roller around which the wiping strip passes after being drawn between the backing roller and the scraping blade, said guide roller being positioned to draw the wiping strip from the edge of the scraping blade at 10 a sharp angle to the plane of the scraping blade.

4. An ink saving attachment for embossing presses and the like, including a backing roller arranged upon one side of 15 the ink wiping strip, a yieldably mounted scraping blade arranged upon the opposite side of the ink wiping strip and disposed in a plane parallel to and spaced from a plane passing through the axis of the backing 20 roller, said scraping blade coöperating with the backing roller to recover the ink from the ink wiping strip and being positioned on the side of the backing roller from which the ink wiping strip is drawn, a 25 solvent receiving trough arranged in advance of the scraping blade, a distributing roller partially submerged in the solvent of the trough and engaging the ink wiping strip to supply solvent thereto for the purpose of softening the ink thereon, and a 30 guide roller around which the ink wiping strip passes from the scraping blade, said guide roller being positioned to draw the ink wiping strip from the scraping blade at 35 a sharp angle thereto.

5. An ink saving attachment for embossing presses and the like, including a U-shaped supporting frame provided at the sides thereof with arms for engagement 40 with the frame of the press, bearings mounted upon the sides of the U-shaped frame, a backing roller journaled between the bearings and arranged upon one side of the ink wiping strip, a bar slidably mounted between the sides of the U-shaped frame, a scraping blade mounted upon the bar and arranged upon the opposite side of the ink wiping strip, yielding means for moving the bar toward the backing roller and causing 45 the scraping blade to coöperate with the backing roller to remove ink from the ink wiping strip, means mounted upon the U-shaped supporting frame for applying solvent to the ink wiping strip before it is engaged by the scraping blade, a guide roller mounted upon the U-shaped frame and around which the ink wiping strip passes from the scraping blade, said guide roller being arranged to draw the ink wiping strip from the scraping blade at a sharp angle, and means for collecting the recovered ink.

6. An ink saving attachment for embossing presses and the like, including a 65 U-shaped supporting frame provided at the

sides thereof with lateral arms for engagement with the press frame, bearings upon the sides of the U-shaped supporting frame, a backing roller journaled between the bearings and arranged upon one side of the ink 70 wiping strip, a bar slidably mounted between the sides of the U-shaped frame, a scraping blade mounted upon the bar and arranged upon the opposite side of the ink wiping strip, yielding means for moving the bar toward the backing roller and causing the scraping blade to coöperate therewith to remove the ink from the ink wiping strip, collars applied to the lateral arms of the supporting frame, arms projecting from 80 the collars and provided with bearings, a solvent distributing roller journaled within the bearings and engaging the ink wiping strip in advance of the scraping blade, means for supplying solvent to the solvent 85 distributing roller, and means for collecting the recovered ink.

7. An ink saving attachment for embossing presses and the like, including a U-shaped supporting frame provided at the 90 sides thereof with lateral arms adapted to engage the press frame, bearings applied to the sides of the U-shaped frame, a backing roller journaled between the bearings and arranged upon one side of the ink wiping strip, a bar slidably mounted between the sides of the U-shaped frame, a scraping blade mounted upon the bar and arranged upon the opposite side of the ink wiping 95 strip, yielding means moving the bar toward the backing roller and causing the scraping blade to coöperate therewith to remove the ink from the ink wiping strip, collars rotatably mounted upon the lateral arms of the supporting frame, means for locking the 100 rollers in an adjusted position, arms projecting from the collars and provided with bearings, a solvent distributing roller journaled within the said bearings and engaging the ink wiping strip in advance of the scraping blade, means for supplying solvent to the solvent 105 distributing roller, and means for collecting the recovered ink.

8. An ink saving attachment for embossing presses and the like, including a U-shaped supporting frame provided at the sides thereof with lateral arms for engagement with the press frame, bearings upon the sides of the U-shaped supporting frame, a backing roller journaled between the bearings and arranged upon one side of the ink wiping strip, a bar slidably mounted between the sides of the U-shaped supporting frame, a scraping blade carried by the bar and arranged upon the opposite side of the ink wiping strip, yielding means moving the bar toward the backing roller and causing the scraping blade to coöperate therewith to remove the ink from the ink wiping strip, 120 collars adjustably mounted upon the arms of 125

- the supporting frame, means for locking the collars in an adjusted position, arms projecting from the collars and provided with bearings, a solvent distributing roller journaled within the said bearings and engaging the ink wiping strip in advance of the scraping blade, means for supplying solvent to the solvent distributing roller, a guide roller journaled upon the supporting frame and around which the ink wiping strip is drawn after passing between the backing roller and the scraping blade, said guide roller being arranged to draw the ink wiping strip from the scraping blade at a sharp angle, and means for collecting the recovered ink.
9. An ink saving attachment for embossing presses and the like, including a U-shaped supporting frame provided at the sides thereof with lateral arms for engagement with the press frame, bearings upon the sides of the U-shaped supporting frame, a backing roller journaled between the bearings and arranged upon one side of the ink wiping strip, a bar slidably mounted between the sides of the U-shaped frame, a scraping blade mounted upon the bar and arranged upon the opposite side of the ink wiping strip, yielding means for moving the bar toward the backing roller and causing the scraping blade to coöperate therewith to remove the ink from the ink wiping strip, collars applied to the lateral arms of the supporting frame, arms projecting from the collars, a solvent receiving trough carried by the said arms, a solvent distributing roller carried by the trough and adapted to apply a solvent from the trough to the ink wiping strip in advance of the scraping blade, and means for collecting the recovered ink.

10. An ink saving attachment for embossing presses and the like, including a U-shaped supporting frame provided at the sides thereof with lateral arms for engagement with the press frame, bearings upon the sides of the U-shaped supporting frame, a backing roller journaled between the bearings and arranged upon one side of the ink wiping strip, a bar slidably mounted between the sides of the U-shaped frame, a scraping blade mounted upon the bar and arranged upon the opposite side of the ink

wiping strip, yielding means for moving the bar toward the backing roller and causing the scraping blade to coöperate therewith to remove the ink from the ink wiping strip, collars applied to the lateral arms of the supporting frame, arms projecting from the collars, a solvent receiving trough removably carried by said arms, and provided at its ends with bearings, a solvent distributing roller journaled within the bearings in the solvent receiving trough and adapted to apply a solvent from the trough to the ink wiping strip in advance of the scraping blades, and means for collecting the recovered ink.

11. An ink saving attachment for embossing presses and the like, including a U-shaped supporting frame provided at the sides thereof with lateral arms for engagement with the press frame, bearings upon the sides of the U-shaped supporting frame, a backing roller journaled between the bearings and arranged upon one side of the ink wiping strip, a bar slidably mounted between the sides of the U-shaped frame, a scraping blade mounted upon the bar and arranged upon the opposite side of the ink wiping strip, yielding means for moving the bar toward the backing roller and causing the scraping blade to coöperate therewith to remove the ink from the ink wiping strip, collars applied to the lateral arms of the supporting frame, arms projecting from the collars and provided at their outer ends with notches, a solvent receiving trough provided at its ends with lugs, said lugs being adapted to fit within the notches in the said arms to removably support the trough thereon, said trough being also provided at its ends with bearings opening at the top of the said trough, a solvent distributing roller removably journaled within the bearings in the trough and adapted to apply a solvent from the trough to the ink wiping strip in advance of the scraping blade, and means for collecting the recovered ink.

In testimony whereof I affix my signature in the presence of two witnesses.

CLYDE T. DEAN.

ANDREW B. FRIES,
JOHN I. NOLAN.
